UNITED STATES PATENT OFFICE.

DAVID BROWN, OF JERSEY CITY, NEW JERSEY, ASSIGNOR OF ONE-HALF
TO CHARLES H. GOODFIELD, OF NEW YORK, N. Y.

FIRE-ESCAPE.

SPECIFICATION forming part of Letters Patent No. 723,194, dated March 17, 1903.

Application filed November 12, 1901. Serial No. 82,050. (No model.)

To all whom it may concern:

Be it known that I, DAVID BROWN, a citizen of the United States, residing at Jersey City, in the county of Hudson and State of New Jersey, have invented new and useful Improvements in Fire-Escapes, of which the following is a specification.

This invention resides in certain novel features of construction, set forth in the following specification and claim, and illustrated in the annexed drawings, in which—

Figure 1 is a side elevation of the device ready for use as a fire-escape. Fig. 2 shows the device raised or out of use. Fig. 3 is a plan view of Fig. 1. Figs. 4 and 5 show a modification.

The fire-escape consists of one or more balconies *a*. These balconies are provided with a floor *b*, sides *c*, and a front *d*. The front portion of railing *d* is provided with a gap *e*. To the bottom *b* are pivoted the links *f*, which are pivoted to the side bars *g* of the ladder. The ladder is provided with side steps or rungs *h*, which are pivoted to the side bars *g*, and also front steps or rungs *i*, which are fastened to the side bars *g*. The ladders can be operated or counterbalanced by means of a weight *j*. The links *f* have fastened to them the railing *k* and bottom *l*, which form a continuation of the balcony-railing when the ladder is open or ready for use. (See Fig. 1.) When the ladder is swung up or closed, (see Fig. 2,) the ladder and the bottom of the railing *k* close the gap in the balcony-railing.

When the swinging platform or bottom *l* is swung into position for use, it forms a continuation of or is on a level with the floor or fixed platform *b*, and the fixed and movable railings *d* and *k* are continuous to one another, so as to guide the user to the gap *e*, leading to the ladder. The links *f* forming in reality part of the movable balcony-floor and being of suitable length, the outer ladder-section *g* is held a suitable distance from the wall or house to be clear of smoke or flame. This outer or front section *g* of the ladder has the lateral sections or rounds made to extend from the outer ladder-section toward the swinging platform or jointed to the

outer ladder-section on the side facing the platforms. Such inner ladder-sections give an increased capacity to the ladder and also fill the gap or space between the outer ladder-section and the platforms. Escape is thus made safe or easy on account of the continuous arrangement or contiguity between the fixed and movable platforms and the ladder-sections.

When not in use or closed up, the device is safe, since, as noted, the swinging balcony-floor *l* in that case closes gap *e* or comes to line with or forms a continuation or closure for railing *d*. Such bottom *l* when raised or closed comes into the vertical plane in which lies railing *d*. The ladder and movable platform or balcony can be held raised by the chain *m*, wound by drum *n*, and held by ratchet and pawl *o p*. The pawl *p* may have a release chain or rope accessible at the various floors of the building, so that in case of fire the occupants at any floor or locality can release the pawl for the ladder to drop or swing into use.

Some modifications can be made in the structure. The ladder could be formed with the rungs *i* as separate pieces from rungs *h*, or the rungs *h* *i* could each be formed integral or from one rod or piece of material suitably bent or shaped to form front and lateral branches.

What I claim as new, and desire to secure by Letters Patent, is—

A fire-escape comprising a stationary platform, a swinging platform suitably connected thereto, outwardly-projecting links carried by said swinging platform, a pair of vertically-extending bars arranged between the outer end of the sides of the swinging platform, a pair of vertically-extending bars arranged between the outer end of said links and pivotally connected to the outer end of said links, horizontally-extending rungs for connecting together the pair of bars arranged between the said links, laterally-extending rungs adapted to pivotally connect the bars arranged between the links to the bars arranged between the sides of said swinging platform, and means connected to one of the

horizontally - extending rungs and adapted when operated to fold said swinging platform against said stationary platform and to fold the bars extending between the links upon 5 the bars extending between the swinging platform.

In testimony whereof I have hereunto set

my hand in the presence of two subscribing witnesses.

DAVID BROWN.
